RUDOLF LORENZ, OF ESSEN, GERMANY, ASSIGNOR TO FRIED. KRUPP AKTIENGESELLSCHAFT, OF ESSEN-ON-THE-RUHR, GERMANY.

GUN WITH RAILWAY GUN-CARRIAGE.

1,360,550.

Specification of Letters Patent. Patented Nov. 30, 1920.

Application filed September 8, 1920. Serial No. 408,981.

To all whom it may concern:

Be it known that I, RUDOLF LORENZ, residing at Essen, Germany, a citizen of the German Republic, have invented certain new and useful Improvements in Guns with Railway Gun-Carriages, of which the of the gun in the transport position.

This invention relates to guns with a railway gun carriage, and the object of the invention is to devise an arrangement which enables the frame of the gun carriage to be effectively supported when the gun is fired and which does not weight the gun carriage during transport.

The invention will be described with reference to the accompanying drawings in which—

Figure 1 is a diagrammatic side elevation of the gun in the transport position,

Fig. 2 is a portion of Fig. 1 on a larger scale, and

Fig. 3 is a view corresponding to Fig. 2 with altered details, partially in section.

Fig. 4 shows on a still larger scale the portion of the supporting carriage shown in Fig. 2 in the firing position, partially in side elevation and partially in section, and

Fig. 5 is a section on the line 5—5 of Fig. 4.

The arrangement shown in Figs. 1, 2, 4 and 5 will be described first.

The railway gun carriage has a frame A, which is carried on two bogies B, B¹ (see Fig. 1). Between these two bogies is arranged a carriage C (see Fig. 1) which is coupled to the front bogie by a connecting rod D or the like. The frame A of the gun carriage can be engaged with the frame C¹ (see Figs. 2, 4 and 5) of the carriage C by means of two jacks E, which are adjustable vertically and relatively to the frame A. For this purpose each jack E is provided with a screw thread e¹ (Fig. 5) which engages in a female screw thread e² in a box-shaped cross piece e³ of the frame A. Each jack E is driven by means of a pair of bevel wheels e⁴, e⁵ mounted on the frame A and adapted to be rotated by means of a hand wheel e⁶.

Between the frame C¹ and the wheel axles C² (see Figs. 2 and 4) of the carriage C supporting springs F are inserted. Two

thrust blocks H intended to rest on the rails G (see Figs. 4 and 5), are movably connected to the frame C¹ by vertical screw spindles J (see Figs. 4 and 5). Each screw spindle J engages in a female screw thread in a bevel wheel i¹ which is prevented from moving vertically by stops e⁶ on the frame C¹. The bevel wheel i¹ gears into a bevel wheel i² the shaft i³ of which is mounted in the frame C¹ and carries a hand wheel i⁴. Through a head i⁵ which forms the lower end of the screw spindle J is passed a leaf spring K (see Figs. 4 and 5) the ends of which engage in guides h¹ (see Fig. 4) in the pressure block H. On the pressure block are provided abutments h² for the heads i⁵ of the spindles J against which the spindles can be supported after corresponding flexion of the springs K.

While the gun is being transported the pressure blocks H are lifted off the rails (see Figs. 1 and 2), and the jacks E are so adjusted that clearance is left between their lower ends and the frame C¹ of the carriage C. The carriage C therefore runs idly. When the gun is to be transferred into the firing position, the pressure blocks are let down so far by rotating the hand wheels i⁴ that the said pressure blocks rest on the rails G. Between the heads i⁵ of the spindles J and the abutments h² clearance is left. The jacks E are then also set up on the frame C¹ of the carriage C by rotating the hand wheels e⁴, (see Figs. 4 and 5). When the gun is fired the bogies B B¹ of the railway carriage take up a portion of the recoil exerted on the frame A of the gun carriage as the frame can bend to the extent to which the frame C¹ of the carriage C yields against the action of the springs F and K. This movement of the frame C¹ ceases immediately the spindles J come into contact with the abutments h² on the pressure blocks H. From this instant the frame of the gun carriage is rigidly supported against the pressure blocks. In this way the recoil is transmitted in the right proportion to the bogies B B¹ and the supporting carriage C and therefore uniformly to as large a portion as possible of the rail bed. In comparison with known supporting devices, which are suspended during transport on the frame of the railway carriage, the arrangement described

possesses the important advantage that its weight does not exert any bending strains on the frame of the gun carriage and does not weight the bogies of the railway gun carriage during transport.

The construction shown in Fig. 3 merely differs from the one described in that the screw spindles *J* are not attached to the pressure blocks by the aid of springs *K* but to the pressure blocks by bolts (*M*). In place thereof there are mounted on the frame *C*¹ of the supporting carriage springs (*N*) which form the abutments for the jacks *E*. In the firing position of the gun the jacks *E* are screwed down so far that they just bear upon the springs *N*. In consequence thereof, an appreciable transmission of pressure by the frame *A* of the gun carriage to the supporting carriage takes place, when the gun is fired only after the springs *N* are stressed. By these means, a favorable distribution of pressure on the bogies *B* *B*¹ and the carriage *C* is insured in this construction also. A similar distribution of pressure could also be obtained without the interposition of springs by allowing a certain amount of play between the jacks *E* and their abutments on the carriage *C* when the gun is in the firing position.

30   Claims:

1. The combination with a railway gun and carriage therefor, of a separate center supporting unit, and means whereby said unit runs idly with said gun carriage when the gun is in transport.
2. A railway gun, which comprises a carriage, a frame supporting said gun, an independent mobile center supporting unit, and means whereby the recoil, when the gun is fired, is distributed between the carriage and the supporting unit.
3. A railway gun and carriage, comprising two sets of bogies, a frame supported on said bogies, a separate supporting unit, and means for connecting said frame centrally thereof to said supporting unit so that the resulting

shock of the recoil is distributed between the bogies and the separate unit.

4. A railway gun and carriage therefor, which comprises sets of bogies, a frame supporting the gun and carried by said bogies, a separate supporting unit adapted to be positioned centrally of the frame, means carried by said unit for supporting it upon the rails of a railway, means for connecting the frame to said separate unit for support thereon, and resilient means within said separate unit whereby the recoil of the gun is first transmitted to the carriage bogies and then to the separate supporting unit.

5. A railway gun and carriage therefor, which comprises two sets of bogies, a frame supporting said gun, a mobile supporting unit, said mobile unit adapted to be placed in a supporting position with respect to the frame, the supporting contact being such that the recoil is transmitted to the mobile unit only after a flexing of the frame.

6. A railway gun and carriage therefor, which comprises two sets of bogies, a frame mounted on said bogies and carrying said gun, a mobile supporting unit, said unit adapted to engage said frame for support thereof, said unit embodying rail-engaging shoes, and means for projecting said shoes to operative position.

7. A railway gun and carriage therefor, which comprises two sets of bogies, a frame mounted on said bogies and carrying said gun, a mobile supporting unit, said unit adapted to engage said frame for support thereof, said unit embodying rail-engaging wheels, rail-engaging shoes, and resilient means disposed between the wheels and shoes and the mobile unit.

The foregoing specification signed at Essen, Germany, this 20th day of May, 1920.

R. LORENZ.

In presence of—

HANS GOTTMANN,

JOSEF WERTZ.
